UNITED STATES PATENT OFFICE.

CHARLES J. CALEY, OF NEW BRITAIN, CONNECTICUT, ASSIGNOR TO THE RUSSELL & ERWIN MANUFACTURING COMPANY, OF NEW BRITAIN, CONNECTICUT, A CORPORATION OF CONNECTICUT.

PLUMB-BOB.

SPECIFICATION forming part of Letters Patent No. 777,242, dated December 13, 1904.

Application filed December 14, 1903. Serial No. 185,017. (No model.)

To all whom it may concern:

Be it known that I, CHARLES J. CALEY, a citizen of the United States, residing at New Britain, in the county of Hartford, State of Connecticut, have invented certain new and useful Improvements in Plumb-Bobs, of which the following is a full, clear, and exact description.

My invention relates to improvements in plumb-bobs, and particularly to the mechanical construction thereof.

The object of my invention is to produce a plumb-bob of suitable form which may be cheaply and economically manufactured and which will subserve with efficiency the purposes of instruments of this character.

The invention consists in the employment of a casing inclosing a load or weight and means for securing these parts together in such a way that their assembling may be simple. The parts are so constructed that a load of any desired weight may be interchangeably employed at will. The particular construction will be seen on an inspection of the accompanying single sheet of drawings, in which—

Figure 1 is a view showing the parts of my improved plumb-bob disassembled and in side elevation. Fig. 2 is a plan view of the plumb-bob. Fig. 3 is a longitudinal cross-section of the same, showing part in elevation. Fig. 4 is a bottom plan view.

The casing is preferably formed of sheet metal and in two parts, the main body 1 and the cap 2, one of which is provided with a fillet and the other with a corresponding recess, forming an overlapping joint, to the more perfectly aline the parts.

3 is a conical point formed, preferably, of hardened metal, as of steel.

4 is a shank attached to the point 3. The screw-threaded portion of the shank 4 screws into a tapped hole in the top of the cap 2 and thus is adapted to draw the parts securely together, the head of the point having a shoulder to abut against the lower end of the casing 1.

5 is a tip, which is screw-threaded on the interior and adapted to be screwed down onto

the upper end of the shank 4. The top of this tip is perforated, as at 6, to provide a passage for the plumb-line, the lower end of which is passed through the opening and knotted on the inside of the tip before securing the tip in place. It will be seen on inspection that this tip may be removed without in any way affecting the security of the other parts. The tip also serves to draw the parts securely into position and act as a thumb-nut, the edge of the tip being preferably knurled in order to afford a better grip.

7 is a load or weight, which is preferably shaped to conform to the interior of the casing to give to the plumb-bob the desired weight. This load is preferably formed of lead and is usually cast. A longitudinal passage-way through the load corresponds to the shank 4 and may be of such a size as will give the load the weight desired. Thus for a heavy plumb-bob the passage through the load would be small, while for a lighter plumb-bob the load would be cored out to a greater extent, so as to make it lighter and of the weight desired. In this manner plumb-bobs may be manufactured of any weight desired by simply making the load of the proper weight and inserting it in the casing and securing it in position by the point and shank.

By this construction the manufacturer may conveniently and economically furnish a complete plumb-bob with one or more extra loads of different weights, so that the user can readily interchange the loads to obtain a bob having the weight desired or necessary for the work which he may have in hand.

What I claim is—

1. A plumb-bob comprising the combination of a casing formed of two shell-like parts having an overlapping joint, a load member fitting into both of said parts, a point at the lower end with a shank extending through said load and having a screw-threaded portion at the upper end, the upper part of said casing being screwed onto said shank and a tip member attached to said shank and arranged for the attachment of the plumb-line.

2. A plumb-bob comprising the combina-

- tion of a casing formed of two shell-like parts, a load member fitting into both of said parts, a point at the lower end with a shank extending through said load and having a screwing threaded portion at the upper end, a tip member attached to said shank and arranged for the attachment of the plumb-line the other parts being held together independently of the tip.
- 5 3. In a plumb-bob the combination of a casing formed of two shell-like portions having overlapping edges, a load member inclosed by said casing, a conical point having a shoulder for supporting said casing and a shank extending through said load, a tip member arranged for the attachment of the plumb-line the other parts being held together independently of said tip.
- 10 4. A plumb-bob comprising a casing formed in two parts, a load inclosed thereby, a removable point at the lower end of said casing
- 15 with a shank extending through said casing and a tip secured to the upper end of said shank having means for the securing of the plumb-line.
5. A plumb-bob comprising a casing formed of two shell-like parts, a point at the lower end, a load removably contained within said casing and constituting the main weight of the bob, a tip at the upper end and a shank for securing said parts together.
6. A plumb-bob comprising a casing formed of the two parts 1 and 2, a load 7 removably fitting therein, a point 3 and a shank 4 for securing the parts together.
- 10 Signed at New Britain, Connecticut, this 10th day of December, 1903.
- 35 CHAS. J. CALEY.
